UNITED STATES PATENT OFFICE.

WELLINGTON PARKER KIDDER, OF GREENWICH, CONNECTICUT, ASSIGNOR TO ROCHESTER INDUSTRIES, INC., OF ROCHESTER, NEW YORK, A CORPORATION OF NEW YORK.

TYPEWRITING MACHINE.

Application filed September 18, 1920, Serial No. 411,146. Renewed January 16, 1924.

To all whom it may concern:

Be it known that I, WELLINGTON PARKER KIDDER, a citizen of the United States, and a resident of Greenwich, in the county of 5 Fairfield and State of Connecticut, have invented certain new and useful Improvements in Typewriting Machines, of which the following is a specification.

This invention relates to a typewriting machine. Its objects and advantages are 10 simplicity of construction; ease of action; lightness of weight; efficiency of impression; silence in operation; the demountability of type bars whereby type bars having one style of printing characters of a 15 given language may be substituted for type bars having other styles of printing characters pertaining to that language; and whereby, if desired, type bars having the 20 printing characters of one language may be substituted for type bars having the printing characters of another language; and a single platen and paper carriage shifting mechanism. Nevertheless the described 25 mechanism for operating the type bars which severally carry a plurality of printing characters is also useful in double shift platen and paper carriage constructions. The paper and platen carriage actuating 30 mechanisms may be useful, even though the type bars carry only one printing character each and may be also useful with other constructions of type bar actuating mechanisms. It is also noted that a typewriting 35 machine embodying the present invention comprises an endwise movable platen and paper carriage which is given a vertical shifting movement to bring the printing point of the platen into one or another of a 40 plurality of positions for receiving the impression of any one of a plurality of characters on a type bar, one above another in the form now shown; the usual transversely extending escapement rack-bar fixed to the 45 carriage being also given a corresponding movement during the vertical shifts of the carriage, and my new escapement movement co-operating with the rack-bar being given a rocking movement for co-operation with the rack-bar.

In the accompanying drawings forming part hereof and illustrating the invention in the best form now known to me:

Fig. 1 is a top plan view of a portion of a 50 typewriting machine embodying the present

invention, only one type bar and its actuating means between the type bar and finger key being shown for greater clearness and the others being removed.

Fig. 2 is a vertical elevational section from front to back of the machine, being in section at a line corresponding to line 2—2 of Fig. 1, and showing the endwise movable platen and paper carriage, and parts carried by it and cooperating with it; the single, 60 key-actuated shift mechanism therefor; and my new carriage shifting mechanism; and one of the numerous identical, key-actuated, type-bar actuating mechanisms. The endwise movable type bar is shown with the 65 printing characters, one above the other and in position of initial rest. The carriage shift key is shown depressed with the carriage in its lowest shift position. The characterized end of the type-bar is shown with 70 an upper corner and an under corner guide for cooperation with type bar guides as in the prior art.

Fig. 3 is a rear elevational view of the machine, and particularly shows, in rear 75 elevation, my new paper and platen carriage escapement mechanism.

Fig. 4 is a top plan view, partly in section at line 4—4 of Fig. 2 of my new escapement mechanism.

Fig. 5 is a perspective view of the type-bar actuating mechanism detached.

Fig. 6 is an end view of the platen and paper carriage detached.

Fig. 7 is a vertical section at line 7—7 of 90 Fig. 1, of the parts shown in Fig. 1, but in the position which they have at the time of impression by the higher character of the type bar.

Fig. 8 is a perspective view of members of 95 the carriage shifting mechanism detached.

In that form of the invention now set forth, a low and approximately rectangular, upstanding main frame comprises a pair of opposed side frames transversely connected 100 by a front member 1 and by a rear member 1^a. The rear ends of the side frames terminate each in an upstanding corner arm 2, forwardly of which the upper edge of each side frame terminates at a distance forwardly of a corner arm 2, thus forming in the upper edge of each side frame a depression as at 4 in order to make room for various operating parts, and to permit endwise travel of the platen and paper carriage 110

past the side frames. The continuous forward edge wall of the arm 2, of the bottom of the depression 4 and of the upper rear end of the side frame is indicated by 5. 5 Forwardly of such depression and extending to the front edge of a type-bar supporting frame, the upper edge of each side frame is horizontal, and the type-bar supporting frame bottom webs are secured at 6 to the 10 upper edges of the horizontal portions of the side frames 3.

The opposite side frames support, at their upper edges, a horizontal, transverse type-bar supporting frame 7 of triangular shape 15 at its under portion and now assumed to be of light weight metal faced at its rear end portion with a steel plate 7^a. The type-bar supporting frame has under horizontal side webs 7^b which rest on and are secured at 6 to the horizontal upper edges of the side frames 3. The frame also comprises a horizontal, dependent, transverse front bar 7^c and is formed with endwise opposed, transverse openings 7^d adjacent the rearward 20 edge of its front bar 7^c. A transverse type-bar cover plate 8, having dependent end arms 8^a each formed with an out-turned flange 8^b and secured to the frame 7 at α , covers all the type bars which stand edge- 25 wise and are endwise reciprocatable between the frame 7 and the cover plate 8; their under and upper edges respectively being in sliding contact with said plates, each of which is provided with opposed guides spaced laterally apart to form an upper guide-way for the upper, and an under guide-way for the under side margin of a type bar. All the type bars are mounted radially to the impression point at p on the platen roll P which is 30 mounted in a vertically raisable and lowerable, transversely movable platen and paper carriage comprising opposed, dependent end plates 9 which travel through the frame depressions 4 during endwise movements of 35 the carriage. The cover plate 8 is provided with dependent pins 8^c and the upper surface of frame 7 is provided with grooves 8^d to form said opposed guide-ways for each type-bar. In Fig. 1, only one guide-way 40 8^d is shown, dot and dash lines indicating the remainder of the guide-ways 8^d and the direction of travel of the type bars.

The platen carriage, end plates 9 have dependent extensions 9^a the under ends of 45 which are transversely connected by a there-to fixed tube 10, the under wall of which has a lengthwise extending slot 11 to permit the carriage to travel endwise in either direction, beyond an end of the transverse, 50 cross-sectionally round, carriage guide and lifting rod 12, on which the tube 10 is endwise-slidably, mounted; the ends of the rod 12 being each fixed to an outward end of a rocker arm 13, and the rearward ends of 55 the rocker arms 13 being each pivoted on

a stud 14 projecting from the inner side of a side frame, corner arm 2, rearwardly of the depressions 4. The bottom edges of the plates 9 are each slotted at 11^a to register with the tube slot 11. 70

The rocker frame thus formed by the rocker shaft 14, the rocker arms 13, and the carriage guide and lifting rod 12, has its front side member which is the guide and lifting rod 12, operative, at its end portions, 75 in the side frame depressions 4 whereby marked compactness of machine construction is effected; the platen carriage being shiftable up and down above the bottom walls of such depressions 4 to raise or lower 80 the impression point on the platen; and the type-bar supporting frame being provided, on its upper side, with as many type bars as are desired; and being also provided with key actuated, type-bar actuating 85 mechanisms, and also with a platen carriage shift mechanism that is in co-operative relation with a carriage feed escape- 90 ment mechanism, the transverse L-shaped rack bar R of which is shown carried by dependent end brackets R' of the carriage, (Figs. 2 and 3).

The type-bar actuating key levers 15 are formed severally with an upturned front end provided with a charactered button head and have their rear ends formed with an upwardly and forwardly extending hook 15^a pivoted on a transverse pivot rod 16 the ends of which are fixed in the upstanding frame members 3 at the front of said depressions 4. All the hooked ends of the type-bar actuating key levers 15 are retained in their pivoted position on the pivot rod 16 by means of a transverse retaining bar 17 each end of which is fixed at 17^a to a 105 side frame. 100

Between its ends, each key lever 15 is provided with a laterally projecting cam roll 18 for engagement by the front edge of an upstanding rockable wiper cam 19, one of 110 which is provided for each key lever, and has its under end pivoted on a transverse straight pivot rod 20, the ends of which are carried by the side frames 3, forwardly of the pivot rod 16. The rear edge 21 of each 115 wiper cam 19 is slightly convex, and when a key lever 15 is depressed, the cam roll 18 which is forward of the upwardly and rearwardly slanting front edge 22 of the wiper cam, rides downwardly on the front edge 22 and thereby rocks the wiper cam rearwardly bringing its convex edge 21 gradually and silently into bearing contact with the forwardly extending straight and horizontal extension 23 of a spiral spring 23^a, 120 the rear end of which is held stationary on a transverse rod 24 the ends of which are carried by the side frames 3, the front end of each horizontal spring extension 23 being secured at 23^b to the under 125 130

end of a wiper cam 19 below the pivot rod 20. To an upper portion of each wiper cam 19, the lower end of an upwardly extending link 25 is pivoted at 26, rearwardly of the pivot rod 20; the upper end of the link being pivoted at 27 to the lower portion of, and between the ends of, an approximately U-shaped lever 28, each end of which is shown forked.

10 The tension of the spring 23^a keeps the front edge 22 of the wiper cam in constant contact with the cam roll 18 on the key lever 15 so that, when in action the key lever is depressed to bring the rear edge of the 15 wiper cam into progressive or gradual rocking contact with the straightened portion 23 of the spring 23^a. The mechanical co-operation of a key lever with the front edge 22 of a wiper cam 19 is silent, there being 20 nothing in the nature of a hammer blow resulting from this rolling contact.

The concave edge of each lever 28 is forwards. The under end, fork arms of each lever 28 straddle an ear 29 dependent from 25 a bracket 30 which is provided, for each lever 28, with a pair of upstanding fork arms 31, the bracket 30 carrying the levers 28 being arranged transversely of the machine and being fixed by clamp screws 32 to the 30 front cross bar 7^c of the type-bar supporting frame, the shape of which is shown in Fig. 1, and the slots 7^d in which make room for mounting and operating the levers 28 and links 25.

35 The upper forward end of each U-shaped lever 28 is provided with a cam roll at 28^a between its fork arms, the cam roll working in the lengthwise extending concavo-convex cam slot 33, the concave edge of 40 which is forwards and the convex edge of which is rearwards, formed in an upstanding cam lever 34, the under end of which is pivoted at 35 between upstanding arms 31 of the bracket 30. The upper front portion 45 of each cam lever 34 is provided with an ear 37 on which the front forked end 38 of a type bar link 39 is pivoted at 40, the rearward end of this link being also forked and formed on its under side with an open, pin-receiving slot 41 for detachable engagement 50 with the pivot pin 42 through and projecting from both sides of the front end of the endwise slidable type-bar 43 which is normally retained in detachable pivoted connection with its link 39 by means of a retaining pin 44 through and projecting from both sides of the type bar, above the rear end of the link which hooks over the pivot pin 42. Thus, by removing the cover plate 8, all the demountable type bars may be readily unhooked and removed for replacement either by type bars having other styles of printing characters belonging to a given language or by type bars having the printing characters of a different language.

The rear end of each type bar is provided with two printing characters *c* one above the other, the type bar having at its upper rear corner and also at its lower rear corner a guide projection *y* as heretofore and for co-operation with guides that are located adjacent the platen, as heretofore and as now indicated by *z*.

Depression of a type-bar actuating key lever 15 throws its wiper cam 19 rearwardly 75 and downwardly against the tension of its spring 23, the corresponding link 25 being then moved downwardly and causing the lever 28 to swing rearwardly, and through its cam roll 28^a forcing the cam lever 34 to swing rearwards and thereby push its type bar, by means of its link 39, to the impression point.

When the front end of a type-bar actuating key lever 15 is relieved of downward pressure, the tension of the then expanded spring 23^a effects an automatic return of the key lever and type bar together with their described connections to initial position of rest.

For my new single key, platen and paper carriage shifting mechanism, the side frames carry a transverse rocker shaft 45 to each end portion of which, adjacent an inner side of a side frame, there is fixed an upwardly extending approximately T-shaped, rocker cam 46 formed with a cam slot 46^a which extends from end to end of the head of the cam above and crosswise of the rocker shaft 45.

The forward end portion 47 of this slot where the cam slot has a forward dwell surface, is, in relation to the shaft 45, lower than the rearward end portion 48 of the slot at which it has a rearward dwell surface.

The rocker cam 46 has a laterally projecting stud 49 above and rearwardly of the rocker shaft 45, and the rear end of a forwardly projecting link 50 is pivoted thereon, the forward end of the link being pivoted at 51 to the lower end of the rearward arm 52 of the inverted V-shaped, single, carriage shift lever 53 which is pivotally supported on an inwardly projecting stud 54 of one of the side frames.

The under apical portion of each approximately V-shaped rocker arm 13 connected with the carriage guide and lifting rod 12, has a laterally projecting stud 55 on its inward face and this stud carries a cam roll 56 which works in the cam slot 46^a of the cam lever 46.

As shown in Fig. 2, the platen and paper carriage is in its lower position, the shift key 53 being in depressed position against the tension of the shift key return spring 57, shown as a coiled spring the rear end of which is fixed at 58 to the rear arm 52 of the shift key and the front end of which is fixed at 59 to a side frame 3, forwardly

of the rear arm 52. When pressure on the shift key is released, contraction of the spring 57 causes the rockable cam lever 46 to rock downwardly and forwardly, thereby 5 causing the under edge of its cam slot to push forwardly and upwardly against the cam roll 56 and thereby lift said rocker frame comprising the carriage guide and lifting rod 12, and the tube 10 to which the 10 carriage end plates are fixed, to bring the impression point of the platen to the upper printing position. In the higher position of the carriage, each cam roll 56 is at a dwell in the higher and rearward portion 15 48 of the cam slots in the opposed rockable cams 46.

The escapement mechanism comprises, for the upstanding teeth of the lengthwise toothed rack-bar R, a pinion 60 fixed on a 20 revoluble spindle 61 at right angles to the carriage feed path. Spindle 61 is journalled in a tubular, spindle holder 60^a which is provided with a flange 61^a at its rear end. One end of a forwardly projecting leaf- 25 spring 62 (Fig. 4) is fixed at 63 to the upper side of a horizontally pivoted trans- 30 verse bracket of which the spindle holder forms a part, the forward end portion of the leaf spring passing under a laterally projecting lug 64 of the spindle holder and the front free end 65 of the spring bearing against the under side of the usual paper guide 66 between which and the platen roll the paper is moved. The spindle 35 61 has loose on it, (Fig. 3) adjacent the rear side of its flange 61^a, a toothed star wheel 67 on the rear face of which there is a projecting stud 68 carrying a spring pressed pawl 69 for co-operation with a 40 ratchet wheel 70 of lesser diameter than the toothed wheel 67 and which is fixed on the rear end of the spindle. The spindle holder carrying bracket comprises oppositely pro- 45 jecting yoke arms 60^b, the ends of which yoke arms are alined. The bracket thus formed is rockably mounted on alined horizontal pivots 71 each carried by an upstand- 50 ing arm 72 of the rear frame member 1^a.

The radial teeth of the toothed star wheel 55 67 are indicated by 73. The pawl 69 on the star wheel in engagement with a tooth of the ratchet wheel 70 prevents rotation of the star wheel in counterclockwise direction but permits rotation of the star wheel in clockwise direction as viewed in Fig. 3. The carriage is drawn in one direction, as usual, by a coiled spring 74, as indicated by the arrow on its drum 75, the pawl and ratchet on the star wheel then preventing 60 rotation of the star wheel, spindle and rack engaging pinion in the direction of the pull of the spring 74, when the type bar is in position of initial rest.

Whenever a type bar is depressed, a ver- 65 tically swinging and horizontally movable

escapement dog 76 pivoted on a stud 77 projecting rearwardly and horizontally from a vertical rocker bracket 78, moves laterally rearwards out of engagement with a tooth of the star wheel; a rigid escapement 70 dog 79 directly in front of the movable dog 76 then engaging such tooth and holding the star wheel from rotation while the printing impression is being made.

The rigid escapement dog 79 is formed 75 by the free end of a rigid horizontal arm 78^a which projects from the upper end of the vertically mounted bracket 78; and in the rearward rocking movement of the rocker bracket 78 the pivoted escapement dog is 80 moved laterally rearwards from under a star wheel tooth. By a follow up motion, the rigid escapement dog is swung into the place of the pivoted dog under the same star wheel tooth.

The upstanding rocker bracket 78 has its ends alined and severally pivoted at 79^a in an arm of a vertical U-shaped bracket 80 which is integral with one of the horizontal yoke arms 60^b of the spindle holding bracket.

The rocker bracket 78 carries on its rear side a pivoted wiper cam 81 the upper edge of which contacts with the under edge of the pivoted escapement dog 76 and the under edge of which contacts with a horizontal straight portion 82 of a coiled spring 83, the free end of the straight portion being hooked through a hole in a horn 84 in the wiper cam adjacent but below its pivot, and the free end of its coiled portion being fixed at 83^a to the upstanding U-shaped bracket 80 which is oscillatable on the horizontal pivots 71.

The star wheel 67 and the pinion spindle 61 are accordingly vibratable in a vertical plane at right angles to and above the rack-bar R; and when the carriage is shifted upwardly, the pinion 60 engaged by the rack is lifted, with its teeth in constant mesh with the upstanding toothed web of the rack-bar R, which is shown L-shape in cross-section; and the carriage, with its rack-bar, and the spindle with its rack-bar engaging pinion and are lifted together.

On the downward shift of the paper carriage, said lifted members descend in unison, the pinion and rack-bar being in constant mesh during such downward shift. The leaf spring 62 is in action during all shifting movements of the carriage, and at all times when the type-bar actuating keys are depressed, and also during the return of the keys to initial positions of rest.

When a line has been printed and it is desired to return the carriage to starting position, the carriage may be manually pushed endwise to effect such return as usual; the pawl 69 on the star wheel 67 then riding freely over the teeth of the ratchet

adjacent the star wheel and fixed on the pinion spindle 59.

When it is desired to return the carriage, mechanically and silently, the rack engaging pinion 60 is raised out of engagement with the rack-bar R by means of a horizontally slidably, release bar 85 (Fig. 3) which is provided with inclined cam slots 86 in which rearwardly projecting studs 87 on the rack-bar work; one end of the release bar having an upturned finger end 88 at a side of the machine and accessible to the operator for manual pressure. The slots 86 are parallel and are formed slantingly in the release bar, the slots extending upwardly and slantingly in a direction away from the upturned finger end 88.

When the release bar is moved inwardly from its position shown in Fig. 3, it is raised by the cam action of the inclined slot walls on the rack-bar studs 87 with the effect of lifting the release bar to a higher level and in so doing pushing its upper edge against the under sides of the yoke arms 60^b that support the star wheel and pinion carrying spindle; this upward movement of the yoke arms being against the yielding resistance of the free end of the leaf spring 62 that is always in gentle contact with the paper guide and which, being a fixed member of the carriage, slides over the free end 65 of the spring.

I have pointed out above that at the moment of impression, the rigid escapement dog is moved into the place just formerly occupied by the pivoted escapement dog under a given star wheel tooth, whereby the star wheel is held from rotation and the paper carriage is held stationary at the moment of impression. In its movement from under the tooth referred to, the pivoted escapement dog is moved, first laterally rearwards by its rocking movement, and is next pressed upwardly by the wiper cam and the wiper cam spring; and is next moved laterally forwards into the space between said star wheel tooth and the next succeeding star wheel tooth and contacts with the latter tooth the rotational descent of which presses the pivoted dog against the upper edge of the wiper cam 81 and depresses the latter against the tension of its spring 83.

The rigid escapement dog 79 has a forwardly projecting lug 89 inwardly of its free end; and this lug has a vertical hole 90, shown square, through it, the hole loosely receiving the upper end of an upstanding lever 91, the lower end of which is pivoted at 92 to the rear transverse frame member 1^a. Between its ends, this lever 91 has pivoted to it at 93, the rear end of a forwardly extending link 94, the front end of which is pivoted at 95 to the rear end 65 of a dependent rocker arm 96 fixed on a

transverse rocker shaft 97, the ends of which are journalled in the side frames of the machine. This rocker shaft 97 is provided near each journalled end with a fixed rocker arm 98, the front ends of the rocker arms 98 being connected by the transverse universal bar 99 of the machine.

All the type bar actuating key levers cross the universal bar and co-operate as usual with the universal bar to force it downwardly, in which movement the escapement mechanism is actuated for swinging the fixed escapement dog into engagement with a star wheel tooth; the depression of the universal bar being against the tension of a coiled spring 100, one end of which is fixed at 101 to the dependent rocker arm 96 and the other end of which is fixed at 102 to the shaft 20. The tension of spring 100 keeps the transverse universal bar 99 for each of the key levers in constant contact with the under edges of the key levers, so that there is no hammering effect between the universal bar and the key levers and the operation of the machine in this respect is also silent; and in this connection it is to be said that the operation of the link 25, lever 28, cam lever 34, link 39, and type bar 43 with its under and upper supporting plates 7 and 8, respectively, is practically silent or noiseless.

The carriage rack-bar R rides on the upper periphery of an anti-friction roll 103 (Fig. 3) which is journalled on a stud 104 carried by the free end of a vertically swinging arm 105, the other end of which is pivoted on a stud 106 projecting from the rear transverse frame member 1^a. A stout coiled spring 107 is located on the stud with one end anchored at 108 in the swinging arm and its other anchored at 109 in the rear transverse frame member, the spring exerting a constant upward pressure on the swinging arm 105 to keep the roll against the under side of the rack-bar R with sufficient pressure nearly to balance the weight of the paper carriage.

In the construction shown, the center of gravity of the carriage is rearwards of the axis of the supporting rod 12. Consequently the carriage leans rearwardly and is therefore provided on its rear side with a transverse fixed web 110, the ends of which are attached to the paper carriage end plates 9. The rear flange 111 of the web is parallel to the printing line position of the platen and is made straight and bears slidably against the front edge of a transverse bar 112, the ends of which are fixed at 113 to the upper edges of the frame corner arms 2. The bar 112 is dimensioned to be laterally springable between its fixed ends; and the opposite end portions of the bar have integral with them a rearwardly projecting, transversely extending truss 114 at 180

the mid-section of which and directly opposed to the impression point at p , the bar is provided with a horizontal adjusting screw 115 threaded in a nut 116 at its front 5 end and at its rear end in a nut 117 fixed to the truss. The front end of the nut 116 is shown pointed and bearing against the springable bar, 112. This is an old construction for the purpose of adjusting the 10 platen forwardly and closer to the extreme rearward limit of the type bar movement, so as to obtain a heavier impression, if desired, at the printing point. A key actuated means for holding the front end arm 53 of the platen shift mechanism down is provided, the key of such locking means being indicated by 118. When the shift key member 53 is depressed, the platen carriage is in its lowermost position. A cushion 119 15 is located at each end of the path of each rocking cam 46. The horizontal yoke structure 60^a, 60^b forms a vibratable pinion-spindle carrier, and the vertical bracket 78 forms a vibratable escapement dog carrier. 20

25 What I claim is:

1. In a typewriting machine, the combination of a type bar having a plurality of printing characters spaced apart one from another; a type bar actuating mechanism; an endwise movable platen and paper carriage provided with a lengthwise extending rack bar for cooperation with an escapement mechanism; an escapement mechanism comprising a vibratable pinion spindle carrier; 30 a revolvable spindle mounted in the carrier; on an end of the spindle, a pinion for engagement with the rack bar; on such other end of the spindle, a star wheel loosely mounted on the spindle; on the star wheel, a pawl; fixed 35 on the other end of the spindle a ratchet wheel for cooperation with the pawl; carried by the vibratable spindle pinion carrier, a vibratable escapement dog carrier provided with a fixed dog, a swingable dog, 40 and a swingable wiper cam for the vibratable dog; and for the wiper cam a spring for returning it to normal position; and a spring for effecting travel of the paper carriage lengthwise in one direction; a key actuated, 45 carriage-shift mechanism operatively connected with the carriage; and mechanism between the escapement mechanism and the type bar actuating mechanism for actuating the escapement mechanism synchronously 50 with the actuation of the type bar actuating mechanism.

2. In a typewriting machine, the combination of an endwise reciprocable type bar; an endwise movable platen and paper carriage; 60 a type bar actuating key; between the type bar and said key a link having one end pivotally connected to the type bar and its other end pivotally connected to a swinging cam; such cam; a lever pivoted at one end 65 to a fixed pivot and being in operative con-

nection with the swinging cam; a link pivotally connected at one end to said lever and at its other end to a swinging wiper cam, a surface of which is in cooperative relation to said key; and a spring connected 70 to said wiper cam and against the tension of which the wiper cam is moved when the said key is depressed; the carriage being provided with a rack bar for cooperation with an escapement mechanism; such escapement mechanism and operative connections 75 between the escapement mechanism and the type bar actuating mechanism.

3. In a typewriting machine, the combination of an endwise reciprocable type bar and 80 a key actuated type bar reciprocating mechanism comprising a member in detachable connection with the type bar; and demountable means for holding the type bar in working position whereby the type bar 85 may be readily removed for replacement by another type bar.

4. In a typewriting machine, the combination of an endwise reciprocable type bar; a type bar actuating key and a mechanism 90 for operatively connecting the type bar and said key, such mechanism comprising a pivoted wiper cam having a cam wall for cooperation with the type bar and also having a cam wall for contact with the straightened 95 extension of a spiral spring, when said key lever is depressed; and such spiral spring; the spring having a straightened extension in the path of the wiper cam and having one end secured to the wiper cam and its 100 other end fixedly secured.

5. The combination, in a typewriting machine, of a paper carriage and paper carriage actuating mechanism with a type head actuating mechanism comprising a depressible and automatically returnable key lever; a rockable wiper cam having opposed cam surfaces; and a coiled spring having a straightened end portion attached to the wiper cam and positioned to be progressively engaged by one of the cam surfaces of the wiper cam, the other end of the coiled spring being anchored to the machine; and the key lever having a member maintained 110 by the tension of said spring in constant contact with the other cam edge of the wiper cam.

6. The combination, in a typewriting machine, of a paper carriage and paper carriage actuating mechanism with a type head actuating mechanism comprising a depressible and automatically returnable key lever; a rockable wiper cam having opposed cam surfaces; and a coiled spring having a straightened end portion attached to the wiper cam and positioned to be progressively engaged by one of the cam surfaces of the wiper cam, the other end of the coiled spring being anchored to the machine; and the key lever having a member maintained 120 125 130

by the tension of said spring in constant contact with the other cam edge of the wiper cam; and a rockable universal bar mechanism; and a spring for keeping the universal bar in constant contact with the under side of the key lever.

7. In a typewriting machine, the combination with a vertically shiftable endwise movable paper carriage and a type head having a plurality of spaced apart printing characters one above another of a type head actuating mechanism comprising an impression key lever and toggle link members between the key lever and type head, and also comprising a swingable wiper cam and a wiper cam and key lever return spring, the wiper cam supporting the key lever in position of rest under tension of the spring, and the wiper cam having a surface which, when the key lever is depressed, progressively engages the spring and puts it under increasing tension until the depressing pressure on the key lever is removed.

8. In a typewriting machine, the combination of a toggle lever actuated type head having a plurality of printing characters; an impression key operatively connected with said toggle lever type head actuating mechanism; an endwise movable and vertically shiftable paper carriage slidably mounted on a transversely extending, upwardly and downwardly shiftable carriage guide and lifting rod; said rod, the carriage being provided with a slotted fixed tube within and by which the rod is embraced; a pair of rocker arms, each pivotally mounted on a stationary member of the machine, and each rocker arm having a cam wall engaging projection and also having an upwardly extending portion fixed in said rod and extending through the tube slot; a transverse rocker shaft journaled in stationary members of the machine and having fixed to it a pair of lengthwise slotted carriage shifting cams for reception of a rocker arm projection; a shift key pivoted to one of said shifting cams; and a shift key return spring, all combined and operating to effect printing and carriage shift movements with a minimum of noise; the machine being con-

structed to carry a cushion at each end of the path of each shifting cam.

9. In a typewriting machine, the combination with a series of key actuated type heads, each having a plurality of printing characters, of a vertically shiftable and endwise movable paper carriage having a track engaging member; a track supporting mechanism pivotally mounted on stationary pivoting means and comprising a rockable, track supporting structure having a cam engaging projection; a rocker shaft journaled in stationary bearings and provided with a fixed rocker cam having a cam surface operatively working with said projection; and, for rocking the rocker shaft and the cam and thereby imparting a rocking movement to the pivotally mounted track supporting mechanism, a key actuated platen shift mechanism comprising a member having a constant pivotal connection with the rocker cam structure.

10. In a typewriting machine, the combination with a vertically shiftable, endwise movable paper carriage and a type head having a plurality of printing characters spaced one above another thereon, of a type head actuating mechanism comprising an impression key lever, toggle link members between the key lever and head, and a wiper cam and spring tending to return said parts to a position of rest, said cam being arranged when said lever is depressed, to progressively engage and tension said spring.

11. In a typewriting machine, the combination with an endwise movable paper carriage provided with a rack bar, of an escapement mechanism comprising a spindle provided with a pinion for meshing engagement with said rack bar, a device supporting said spindle for tilting movement to carry said pinion into and out of engagement with said rack bar to release the latter, and means for effecting said tilting movement of said spindle.

Signed at New York, in the county of New York and State of New York, this 20th day of August A. D. 1920.

WELLINGTON PARKER KIDDER.
